CLAIM

The ornamental design for a pre-shaped spinal rod for spinal fixation system, as shown and described.

DESCRIPTION

1.-2. Pre-shaped spinal rod for spinal fixation system

1.1 : Perspective

1.2 : Enlarged

1.3 : Left

1.4 : Right

1.5 : Front

1.6 : Top

1.7 : Back

1.8 : Bottom

2.1 : Perspective

2.2 : Enlarged

2.3 : Left

2.4 : Right

2.5 : Front

2.6 : Top

2.7 : Back

2.8 : Bottom

Fig. 1.1 is a perspective view of a pre-shaped spinal rod for spinal fixation system; fig. 1.2 is an enlarged view of a part of the embodiment of fig. 1.1; fig. 1.3 is a left side view of the embodiment of fig. 1.1; fig. 1.4 is a right side view of the embodiment of fig. 1.1; fig. 1.5 is a front view of the embodiment of fig. 1.1; fig. 1.6 is a rear view of the embodiment of fig. 1.1; fig. 1.7 is a top view of the embodiment of fig. 1.1; fig. 1.8 is a bottom view of the embodiment of fig. 1.1; fig. 2.1 is a perspective view of another embodiment of a pre-shaped spinal rod for spinal fixation system; fig. 2.2 is an enlarged view of a part of the embodiment of fig. 2.1; fig. 2.3 is a left side view of the embodiment of fig. 2.1; fig. 2.4 is a right side view of the embodiment of fig. 2.1; fig. 2.5 is a front view of the embodiment of fig. 2.1; fig. 2.6 is a rear view of the embodiment of fig. 2.1; fig. 2.7 is a top view of the embodiment of fig. 2.1; fig. 2.8 is a bottom view of the embodiment of fig. 2.1.

In the 1.2 and 2.2 the dash-dot-dash broken lines are for the purpose of illustrating boundaries of an enlarged portion of the pre-shaped spinal rod for spinal fixation system only and forms a part of the claimed design.
